ELECTRIC SWITCH AND TERMINAL

Filed Feb. 18, 1927

UNITED STATES PATENT OFFICE

JOSEPH D. WOOD, OF WOLLASTON, MASSACHUSETTS, ASSIGNEE TO CONDIT ELECTRICAL
MANUFACTURING COMPANY, OF SOUTH BOSTON, MASSACHUSETTS, A CORPORATION
OF MASSACHUSETTS

ELECTRIC SWITCH AND TERMINAL

Application filed February 18, 1927. Serial No. 169,540.

This invention relates to electric switches and has for an object the provision of an improved form of stationary switch member characterized by having a conducting stud and a contact member integral therewith.

A further object is the provision of inexpensive and reliable means for securing the conducting stud within its insulating bushing.

10 A further object is generally to improve the construction of electric switches.

Figs. 1 and 2 are front and side elevations respectively of a stationary switch member or terminal for an electric switch and embodying the invention.

Fig. 3 is a sectional elevation through the switch member.

Fig. 4 is a plan view of the switch member of Fig. 1.

Fig. 5 is a perspective detail illustrating the manner of attaching the auxiliary contact member to the stationary switch member.

Fig. 6 is an elevation, in detail, illustrating a modified arrangement for securing the conducting stud to its insulating bushing.

Fig. 7 is a plan view of Fig. 6.

The stationary switch member or terminal embodying this invention includes a generally rectangular insulating bushing 10 of substantial length having flat upper and lower faces 12 and 14 respectively and a generally rectangular outstanding integral attaching flange 16 intermediate its ends. The bushing is extended through a rectangular opening 18 in a supporting plate 20, with the flange seated upon the plate. The dimensions of the opening closely approximate the cross-sectional dimension of the bushing under the flange, whereby the bushing is supported against angular displacement in said plate. The bushing is secured detachably in the aforesaid relation by a pair of rigid clamping plates 22 which are disposed on opposite sides of the bushing upon the flange and have opposed inwardly directed arms 24 closely overlying opposite sides of the bushing. Clamping bolts 26 are passed through said plates and the supporting plate 20 whereby 50 to bind the bushing-flange between them.

The bushing is provided with a substantially rectangular passage 28 therethrough which is extended along its longitudinal axis and a conducting-stud 30 having a corresponding rectangular cross-section is received detachably in said passage and is extended below the lower end of the bushing and also thereabove to provide a line-connecting section 32. The lower end of said stud is reflexed at substantially right angles with the body portion thereof to provide an integral main-contact-member 34 having a flat lower contact face adapted to be engaged by the main current-carrying or bridging member 36, see Fig. 3, of the cooperating movable switch member. By the provision of an integral main contact member and stud, contact resistance troubles, such as heating, common with the usual construction of separate stud and contact members, are obviated, especially in relatively high current-carrying capacity switches, with which this invention is more particularly concerned.

The stud is also provided with an auxiliary contact, or arcing member 38 of more or less L-shape, having a shank 40 which is detachably secured to the stud by a single bolt or screw 42 and having a contact section 44 which is opposed to the main contact member 36 and is in approximately the same horizontal plane therewith and is adapted to be engaged by the cooperating movable arcing member 46. The stationary arcing member is additionally secured to the stud against angular displacement thereon by a strap-member 48 which is interposed between said screw 42 and the shank of the contact member. Said strap and member is of general channel-shape and has side-walls 50 which closely engage the opposite side faces of the shank, intermediate outstanding sections 50a which overlie the broad face of the stud on opposite sides of the shank, and reflexed opposed ends which closely fit the opposite sides or edges of the stud, thereby preventing rotation of the contact member.

The conducting stud is secured detachably within the insulating bushing by means including a plate 52 disposed upon the stud and bearing against the lower face of the

bushing. A pin 54 is received loosely in an aperture in said stud and is extended in both directions beyond the stud and bears against the plate. Said plate has a depending peripheral flange 56 which overlies the opposite ends of the pin and prevents displacement thereof. The upper end of the stud is formed with preferably a square opening 58 therethrough in which a pressure-bar 60 is loosely received. Clamping screws 62 are screwed in the ends of said bar, on opposite sides of said stud and bear against a pressure plate 63 seated on the upper end of the bushing, whereby to cooperate with the pin 54 in clamping the stud to the bushing. The stud can be withdrawn from the bushing upon the removal of the screws 62 and the bar 60. In the modification illustrated in Fig. 6, a U-shaped locking lever 64 is detachably pivotally connected with the stud by a bolt 66 and has cam-projections 68 located on opposite sides of the stud which bear upon a plate 70 seated upon the upper end of the bushing for the same purpose.

25 The auxiliary contact member and terminal herein claimed are described in my co-pending application Serial No. 169,341, filed February 18, 1927.

I claim:

- 30 1. A terminal for an electrical apparatus comprising an insulating bushing, a conductor disposed therein, and clamping means for said conductor comprising a pin extended loosely through said conductor and bearing against the lower face of said bushing, a pressure-bar extended loosely through said conductor at the upper end thereof, and clamping-screws carried detachably by said bar on opposite sides of said conductor disposed above and bearing against the upper end of said bushing.
- 35 2. A terminal for an electrical apparatus comprising an insulating bushing, a conductor disposed therein, and clamping means for said conductor comprising a pin extended loosely through said conductor and bearing against the lower face of said bushing, means to secure said pin against axial displacement including a plate on the lower end of said bushing and surrounding said conductor and having opposed depending flanges extended over the ends of said pin, a pressure-bar extended loosely through said conductor at the upper end thereof, and clamping-screws carried detachably by said bar on opposite sides of said conductor disposed above and bearing against the upper end of said bushing.
- 40 3. An electric switch having a terminal including a rectangular conductor, a contact member carried by said conductor having a shank abutting against a broad face of said conductor within the edges thereof, and clamping means for said contact member including a screw passed through said shank and connected with said conductor, and a

strap interposed between said screw and shank and having opposed walls closely fitting over the opposite sides of said shank and intermediate sections lying upon the broad face of said conductor and reflexed opposed ends at the ends of said intermediate sections closely fitting over the side faces of said conductor.

4. A stationary switch member including a rigid vertical porcelain bushing of rectangular section having a rectangular axial passage therethrough, a rigid conductor of corresponding rectangular section extended removably through said passage and beyond both the upper and lower ends of said bushing, the upper end of said conductor constituting connecting means for a circuit lead, and the lower end of said conductor having an angularly-disposed free end which constitutes a contact member, and means securing said conductor removably in the aforesaid relation including a pin which is passed through and is extended beyond the opposite sides of said conductor under said bushing, a bearing plate having a rectangular conductor-opening engaged with the bottom end of said bushing over said conductor and having opposed depending projections which overlie the opposite ends of said pin and restrain it in the aforesaid relation, a second bearing plate having a rectangular conductor-opening engaged with the upper end of said bushing over said conductor, a transverse member extended removably through a passage in said conductor above said second bearing plate and in opposite directions beyond said conductor having removable means which bear downwardly on said second bearing plate on opposite sides of said conductor and thereby force said bushing against said lower pin.

5. A switch member for an electric switch comprising an insulating bushing, a conductor extended removably therethrough, and means to secure the conductor fixedly within the bushing comprising a pin which is extended through the conductor at the lower end thereof and which abuts against the bottom of the bushing, and a pair of clamping devices which are disposed above the bushing on opposite sides of the conductor and have their lower ends bearing upon the top of said bushing, whereby to draw the conductor upwardly to maintain said pin in pressure engagement with the bottom of the bushing, and a connecting member which supports said clamping devices and which is passed removably through the top of and is carried by said conductor.

In testimony whereof, I have signed my name to this specification.

JOSEPH D. WOOD.
